US00D875666S

(12) **United States Design Patent** (10) **Patent No.:** **US D875,666 S**
(45) **Date of Patent:** **** Feb. 18, 2020**

(54) **BATTERY PACK FOR PORTABLE ELECTRONIC DEVICE**

(71) Applicant: **Mizco International Inc.**, Avenel, NJ (US)

(72) Inventors: **Maurice Mizrahi**, Brooklyn, NY (US); **David Goetz**, Avenel, NJ (US)

(73) Assignee: **MIZCO INTERNATIONAL INC.**, Cranford, NJ (US)

(**) Term: **15 Years**

(21) Appl. No.: **29/589,814**

(22) Filed: **Jan. 4, 2017**

(51) **LOC (12) Cl. 13-02**

(52) **U.S. Cl.**

USPC **D13/103**

(57) **CLAIM**

The ornamental design for a battery pack for portable electronic device, substantially as shown and described.

DESCRIPTION

FIG. 1 is a top, front perspective view of a battery pack for portable electronic device of our new design.

FIG. 2 is a top, rear perspective view thereof.

FIG. 3 is another top, front perspective view thereof.

FIG. 4 is another top, rear perspective view thereof.

FIG. 5 is a bottom, front perspective view thereof.

FIG. 6 is a bottom, rear perspective view thereof.

FIG. 7 is a front elevation view thereof.

FIG. 8 is a rear elevation view thereof.

FIG. 9 is a right side elevation view thereof.

FIG. 10 is a left side elevation view thereof.

FIG. 11 is a top plan view thereof; and,

FIG. 12 is a bottom plan view thereof.

The broken line showing of a camera in FIGS. 1 and 2 is for the purpose of illustrating environmental subject matter that forms no part of the claimed design. The remaining broken lines in the drawings are for the purpose of illustrating portions of the battery pack for portable electronic device that form no part of the claimed design.

1 Claim, 12 Drawing Sheets
